Atty.

UNITED STATES PATENT OFFICE.

ROBERT J. NELSON, OF CHICAGO, ILLINOIS.

BOILER-FURNACE.

1,365,943.

Specification of Letters Patent. Patented Jan. 18, 1921.

Application filed December 16, 1918. Serial No. 266,944.

To all whom it may concern:

Be it known that I, ROBERT J. NELSON, a citizen of the United States, residing at Chicago, in the county of Cook and State of Illinois, have invented certain new and useful Improvements in Boiler-Furnaces, of which the following is a description, reference being had to the accompanying drawings, forming a part of this specification, in which corresponding numerals of reference in the different figures indicate like parts.

The primary object of my invention is to provide a simple, cheap and effective boiler furnace which will be so constructed as to insure complete combustion of the gases rising from the forward portion of the grate, by causing them to be passed downwardly through a flue or conduit formed in the space between juxtaposed baffle-plate members located in the fire-box above the grate and between the forward and rear ends thereof, into a secondary space or combustion chamber behind said baffle-plate members and in advance of the boiler flues.

A further object is to so hinge or pivot said baffle-plate members as to enable them to be moved at will into abnormal, non-obstructing positions so as to provide for ready access to the boiler flues for cleaning or re-pairing them.

Again, it is my purpose to provide water-cooling means for cooling said baffle-plate members and their hinged supports, while preventing leakage through the intervening joints:—all of which is hereinafter more particularly described and definitely pointed out in the claims.

In the drawings,

Figure 1, is a longitudinal vertical section 40 of a boiler furnace taken upon line 1—1, Fig. 2, viewed in the direction of the arrow there shown,

Fig. 2, is a horizontal section in plan taken upon the line 2—2, Fig. 1,

Fig. 3 is a vertical section taken upon the line 3—3, Fig. 1, viewed in the direction of the arrow there shown, a portion of the hinged baffle-plate member being broken away to show the water supply pipe therein, 50 and

Fig. 4, is an enlarged vertical section in detail of one of the hinged joints, showing improved packing means therefor.

Referring to the drawings, 1 indicates generally a stationary boiler furnace of well known construction, having the usual grate

2, fire-wall 3, at the rear of the grâte, hollow transverse water-leg 4, in communication with the boiler and supported upon said fire-wall, flues 5 and parallel water-legs 6, 60 extending forward upon opposite sides of the grâte to the front of the boiler and forming a part of the usual fire-box or combustion chamber.

Located in the upper part of the fire-box 65 and transversely thereof, is a baffle-plate or diaphragm 7, preferably formed from fire-clay or other refractory material, which feature consists of a flat slab arranged to fit closely against the top and side-walls and 70 extend downwardly from the roof of the fire-box a predetermined distance, said slab being supported in place by means of a channel-iron 8, located at the top of the swinging gates hereinafter described, and extending 75 from the channel iron to the top of the furnace chamber or fire box, the ends of which are rigidly secured to the side walls of the fire-box.

Tapped into the side-walls 9, of the fire-box, upon opposite sides of the furnace, are hollow nipples 10, 10, one above the other as in the manner shown in Fig. 3. Said nipples are, in turn, connected by means of elbow members 11, 11, one of which is shown in 85 Fig. 1, with short vertical pipes 12 in alignment with each other and which, in turn, are connected in a well known way by means of threaded sleeves 13, one of which is shown in Fig. 4, with an intervening perforated 90 pipe 14, best shown in Fig. 3. The short pipes 12, at top and bottom serve as pivotal supports for counterpart baffle-plate members generally designated by 15 and 16, respectively. In the example illustrated, 95 each of said baffle-plate members is made hollow throughout, and may either be formed from cast metal or steel plates welded together so as to make them integral. The latter are preferred. The member 15

consists of a main hollow upright portion rounded at the front, as shown at 17, and squared at the rear, as shown at 17^a, to engage the side-wall 9 and form a stop. Said upright portion is provided with hollow extensions or upright wings 18 and 19, extending laterally therefrom; said extensions being spaced apart and preferably substantially parallel to each other. The walls of said extensions are preferably connected by 110 stay-bolts 15^a. It will be noted that the extension 18 is longer than 19. The member

16 is constructed in every respect like the member 15, except that the short and long extensions 20 and 21, Fig. 2, are reversed with respect to their fellows, so as to stand 5 in staggered relation thereto, for the purpose of breaking joints. The extensions 18 and 20 are preferably provided upon their meeting edges with overlapping counterpart hollow flanges or offsets 18^a and 20^a, 10 Fig. 2, while the parts 19 and 21 are formed with like features 19^a and 21^a, for the purpose of enabling the baffle-plate to be adjusted to furnaces of varying width while maintaining a substantial closure for preventing 15 a direct passage of the gases. The top of all of said extensions are, preferably, upon substantially the same level, namely, that of the lower edge of the slab 7, or its support which is located directly above and in the 20 same plane with the extension members 19 and 21, when the latter are in their respective normal positions. The first members or extensions 18 and 20 are of greater upright measurement than their fellows 19 and 21 25 in the rear, being extended downwardly, so that their lower edges may be in normal contact with the fuel, as indicated in Fig. 1, while the lower edges of the extensions or wings 19 and 21 are above that level. 30 I prefer to place the baffle-plate members in a plane somewhat nearer to the back than to the front of the grate, substantially as indicated, so that the forward combustion chamber for the generation of gases 35 will be larger than that at the rear. The space between the front and rear baffle-plate members or wings serves as a downward flue or conduit for the passage of the gases which are caused to rise from the fresh 40 fuel upon the front of the grate, and, as indicated, by the arrows, are caused to pass downwardly through said flue and outwardly into the rear combustion chamber in the zone of the most intense heat, thereby 45 insuring complete combustion.

Each of the hinged baffle-plate members is free to swing upon a vertical axis and their free ends may be moved forwardly so that they may stand parallel and adjacent 50 to the side walls of the fire-box with which they are respectively connected, thereby leaving the fire-box unobstructed for cleaning or repairs.

The hollow support to which each baffle-plate member is hinged is intended to serve 55 as a means for water communication between the boiler and the interior of said member; and the manner of constructing the jointed and hinged connections with said support is of the utmost importance; not only for insuring the durability of the structure but for preventing leakage. This construction will now be described.

Formed in the upper and lower ends of 60 the cylindrical portions of each baffle-plate

member and upon a common axis are circular depressions, one of which is shown in Fig. 4, having a cylindrical wall 22, a web portion 23, and an annular flange 24, which forms a shoulder adapted to bear loosely 70 against the end of the sleeve 13.

An annular member generally designated by 25, has outer and inner concentric walls 26 and 27, which are connected by means of an integral web 28, the outer face of which 75 is arranged to contact with the inner face of the web 23. An opening 29 in the web 23 is intended to register with an opening 30 in the web 28. The latter may be held in such registering position by means of a screw 31 so which connects the two webs. The parts 26 and 27 are of such diameters, respectively, as to leave an annular space between the wall 22 and the wall 26 and a similar space between the wall 27 and the surface of the 85 tube 12. The base of the web 28 is made to fill the entire space between the wall 22 and the tube 12, and is beveled upon opposite edges, as indicated at 32 and 33. The exterior of the part 26 is threaded to receive 90 an internally threaded flange 34 connected by means of a web 35 with a sleeve 36, adapted to fit the pipe 12, and arranged to extend in opposite directions from the web 35, the outer portion being made polygonal 95 to enable it to be turned. The inner end of the part 34 is beveled as shown at 37 in an opposite direction from the bevel 32 and the inner end of the sleeve 36 is beveled as shown as 38, in an opposite direction from 100 that of the bevel 33. A packing 39 is interposed between the surfaces 32 and 37, and a like packing 40, between the surfaces 33 and 38. When the sleeve 36 is screwed down the packing is compressed and all leakage of the 105 joints is thereby prevented.

The water in the boiler is free to circulate through the nipples 10, the pipes 12 and thence through the perforations in the pipe 14 to the interior of the hollow baffle-plate 110 members 15 and 16. From thence it is free to pass through the openings 29 and 30 into the annular space between the walls 26 and 27. It will thus be seen that all of the surfaces which contact and are adapted to move 115 upon each other, including the packing, are water cooled and fully protected from being injured by heat.

The baffle-plate members are intended to stand normally in the transverse positions 120 indicated in Figs. 1 and 2, in which they are held against backward movement by the stops 17^a. Whenever necessary to clean or repair the flues, a hooked rod may be placed beneath the respective members in turn, 125 when they may be readily swung forward upon their hinges to the respective sides of the fire-box. The bearing members may be caused to turn upon the pipes 12 like a gate upon its hinges.

I do not wish to be limited to the construction shown and described inasmuch as it may be varied without departing from the spirit of the invention. For example, it is

5 obvious that the hinged baffle-plate members may be constructed of a refractory material and arranged to be operated in the same way, but I prefer to employ the water-cooling feature.

10 Having thus described my invention, I claim:

1. The combination with a furnace having a grate and a combustion-chamber above it, of counterpart baffle-plate members hinged

15 upon substantially vertical axes upon opposite sides of the combustion-chamber between the ends of the grate, each member being provided with lateral upright extensions to form, when in normal positions,

20 juxtaposed forward and rear baffle-plates extending across the furnace, the forward ones being in a plane in advance of and extending downwardly from a level below the top of the combustion-chamber to one below

25 the normal level of the fuel, while the lower edges of the rear ones are upon a higher level, and means for closing the space in said combustion-chamber above said rear baffle-plates.

30 2. The combination with a furnace having a grate and a combustion-chamber above it, of hollow counterpart baffle-plate members hinged upon substantially vertical axes upon opposite sides of the grate, each

35 member being provided with lateral upright extensions to form, when in normal positions, juxtaposed forward and rear baffle-plates extending across the combustion-chamber, the forward ones being in a

40 plane in advance of and extending downwardly from a level below the top of the combustion-chamber to one below the normal level of the fuel, the lower edges of the rear ones being above said level, means for

45 closing the space across said combustion-chamber above said rear baffle-plates, and means for causing a water-circulation from the boiler through said baffle-plates.

3. A furnace having a grate and a combustion-chamber above it, of a stationary transverse baffle-wall extending downwardly from the top of the combustion-chamber between the front and rear ends thereof to a predetermined level, counterpart baffle-plate

55 members hinged upon upright water-containing hollow tubes located upon opposite sides of the furnace below said wall, said member having laterally extended upright wings arranged to form, when in normal positions,

60 forward and rear baffle-plates extending jointly across the combustion-chamber and spaced apart to form a downward flue between them, the forward ones extending downwardly from a level below the top

65 of the combustion chamber to one below the normal level of the fuel, the rear ones forming in effect a downward continuation of said wall and having their lower edges above said normal fuel level.

4. In a furnace having a grate and a combustion-chamber above it, baffle-plate members hinged upon upright axes located upon opposite sides of the furnace, said members having laterally extended upright wings arranged to form, when in normal positions, 70 forward and rear baffle-plates extending in joint relation across the combustion-chamber between said upright axes and spaced apart to form a downward flue between them leading from the forward part to the rear of the combustion-chamber, the forward plates extending downwardly from a level below the top of the combustion-chamber to one below the normal fuel level while the rear ones form in effect a downward continuation of said wall, their lower edges above said normal fuel level, and means for causing a water-circulation from the boiler through said baffle-plates and the supporting 75 80 85 90 95 100 105 110 115 120 125 130

5. In a furnace having a grate and a combustion-chamber above it, the combination of a pair of oppositely swinging hollow baffle-plate members hinged upon upright axes located upon opposite sides of the furnace, said members having laterally extended upright wings arranged to form, when in normal positions, forward and rear baffle-plates extending in joint relation across the combustion-chamber between said 100 upright axes and spaced apart to form a downward flue between them in open communication with the front and rear portions of the combustion-chamber, the forward plates extending downwardly from a predetermined level below the top of the combustion-chamber to a position below the normal fuel level, while the rear ones extend from the upper position of the combustion chamber to a point above said normal fuel 110 level, and hollow hinge-supports for said members, located on opposite sides of the furnace chamber and rigidly attached to the side-walls of the furnace, said supports being in open communication with the 115 boiler and with the interior of said members.

6. The combination with a furnace having a grate and a combustion-chamber above it, of a hollow winged gate having a space between the wings to form a downward flue 120 for the passage of unconsumed gases, said gate being hinged upon an upright axis located adjacent to a side-wall of the combustion-chamber, means for permitting a circulation of water from the boiler through 125 the hinge of said gate to the interior of the latter, means for packing the joints of said hinge to prevent leakage, means for water-cooling said packing, and a second double-winged hinged gate provided with an up-

right water-cooled supporting hinge member located at the opposite side of the furnace from the first-mentioned hinged gate, and adapted to swing into and out of engagement with the latter.

7. The combination with a furnace having a grate and a combustion-chamber above it, of a hollow winged gate to form a downward flue for the passage of unconsumed gases from the front to the rear of the combustion-chamber, an upright tube attached to the side-wall of the combustion-chamber and extending from the bottom of said gate upward on the inside of the gate to a point above the top of the same, and adapted to communicate with the water-containing
- 10
- 15

space of the boiler to form a hinge support for said gate, said support permitting a flow of water into said gate, annular packing members for admitting a flow of water into 20 said gate, annular packing members for packing the hinged joints, and means for admitting a flow of water into the annular spaces in said packing members.

In testimony whereof I have signed this 25 specification in the presence of two subscribing witnesses, this thirteenth day of December, 1918.

ROBERT J. NELSON.
